UNITED STATES PATENT OFFICE.

ROBERT ROBERTS AND JOHN L. KNIGHT, OF NEW YORK, N. Y.

LIFE-RAFT.

SPECIFICATION forming part of Letters Patent No. 236,721, dated January 18, 1881.

Application filed August 4, 1880. (No model.)

To all whom it may concern:

Be it known that we, ROBERT ROBERTS and JOHN L. KNIGHT, both of New York city, have invented certain new and useful Improvements 5 in Life-Rafts, of which the following is a specification.

Our invention aims to provide a life-raft which, while being quite compact when on deck, shall be capable of rapid and easy exten- 10 sion to afford large capacity for passengers, with great buoyancy when launched, and at the same time embody a strong, light, and safe construction.

To these ends our invention is embodied in 15 the special construction of the floats, the mode of connecting and bracing them together, and in the attachment of the gunwale or rowlock-bar thereto.

A leading feature of our invention also con- 20 sists in a folding extensible construction of the platform or deck, and in an arrangement of guard or life lines connecting thereto, as hereinafter fully set forth.

Figure 1 of the drawings annexed presents 25 a plan view of our improved life-raft with the platform extended and one float shown partly in section. Fig. 2 is a central longitudinal section, and Fig. 3 is a cross-section thereof.

In the drawings, *a a* indicate the floats of 30 the raft, which, according to our invention, consist of metal tubes or cylinders formed of a strip or sheet of metal wound spirally, as illustrated, the spiral edges being lapped, riveted, and the joints soldered, or the whole tube subsequently 35 galvanized, thus rendering the joint perfectly tight. This construction is not only simple and inexpensive, but very light and strong, as the lapped and riveted joint running spirally around the float acts as a brace or corruga- 40 tion, which strengthens it at all points. The ends of the tubular floats are pointed or conical, as usual; but a further novel feature of the floats consists in a smaller float, *a'*, arranged within the outer larger float, with an 45 air-space between them, so that should the outer float become punctured the inner one, being tight, will sustain the raft. The ends of the smaller float are supported in the pointed ends of the larger one, and its middle is sup- 50 ported by a ring or collar, *b*, arranged between the inner and outer tubes, as seen best in Fig.

1. The opposite floats of the raft, as illustrated, are placed parallel to each other at a suitable distance, and are rigidly connected together with the supporting platform or deck arranged between them, as usual; but the special manner of connection is novel, consisting of metal pipes with screw-connections, after the manner of ordinary pipe-fittings. Thus a number of metal plates, *c c*, are riveted or otherwise fixed on the inner sides of the floats at their center lines, as seen in each figure of the drawings, which plates have projecting threaded nipples, into which metal rods or tubes *d d* are screwed, and which meet or converge midway between the floats in the form of a series of *X*'s, where their converging ends are screwed with an opposite thread into the branches of the pipe-crosses *e*, which thus firmly join the several rods of each *X* together. This mode 65 of bracing and connecting the floats is not only obviously strong and light, but is very simple and cheap and braces the floats together in a very rigid manner.

The slats of the deck or platform *f* are supported on three cross bars or beams, *g*, extending between the floats, one at the center and one at each end, which are held at the ends by metal straps *h*, which encircle the floats, and are riveted or otherwise secured thereto, 80 as fully shown in the drawings, thus rendering the connection of the deck with the floats strong and safe.

In life-rafts of this class as heretofore made it has been found that the buoyancy of the 85 floats is greater than the weight of the utmost number of persons which their decks can accommodate. Now it is, of course, desirable to have the decks of the greatest practicable extent or capacity, so as to accommodate as large 90 a number of persons as the raft can properly float. This we accomplish by providing the deck with extensible sections, preferably at each end, as seen at *k k* in Figs. 1 and 2. These extensible sections are hinged, like folding leaves, to the ends of the deck, as illustrated, and they are preferably each half the length of the deck, so that they can meet at the center of the deck when folded inward, and be there fastened by a suitable catch, (not shown,) 95 so as to bring the raft within a compact space when aboard ship. When the raft is launched,

however, the extensions or folding leaves *kk* may be unfastened and swung out on a level with the main deck *f*, as shown in Figs. 1 and 2, thus doubling the extent of the deck or platform, and hence greatly increasing the efficiency of the raft and its capacity to support passengers, so that its life-saving power is thus greatly enhanced. Smaller folding leaves *ll* are hinged to the sides of the main leaves *kk*, so as to fold out sidewise, as shown in Fig. 1, and thus still further extend the supporting-platform at the ends of the floats.

For the greater security of the raft and safety of its passengers, we provide a novel arrangement of life-lines on each side of the raft, to afford a hold to the passengers thereon. This is shown clearly in Fig. 2, but is not represented in Fig. 1, in order to avoid confusion of parts.

20 A rock-shaft, *m*, preferably made of metal pipe, is screwed at each end into pipe *T*'s, which are journaled in eyes close to the deck at each end thereof, as shown. From these *T*'s standards *n* extend, as shown, also preferably made 25 of pipe, and each tipped with a screw-cap having an eye at each side, from which a cord or chain, *o o'*, extends in one direction to the end of the deck-extensions *kk*, and in the other direction to the opposite end of the deck *f*, as fully 30 shown in Fig. 2, and, as may be seen in Fig. 3, the arrangement of lines is the same on each side of the raft.

It may be now observed that the act of swinging out the extensible sections *kk* will bring the standards *n* in vertical position, where they may be rigidly held by catches, and will cause the life-lines to assume their effective positions, which afford secure and ample hold for the passengers and protect them 35 from falling or becoming washed overboard. It may be also seen that these lines, with their standards, act as a truss to partly support the extensible sections, the weight on which will always keep the lines taut and serviceable; 40 and it may be further observed that the pivoted arrangement of the standards, in connection with their rock-shaft *m*, enables the lines and standards to readily assume a recumbent position and fold compactly under the extensible sections *kk* when the same are folded 45 in against the deck, as may be seen on reference to the submerged side of the raft in Fig. 2.

It may now be stated that the several described features of the raft—viz., the deck, folding leaves thereof, life-lines, &c.—are double—that is, duplicated on each side of the raft—so that when the raft is launched it will be in a condition for instant use whichever side is 50 the uppermost, as may be readily seen from Figs 2 and 3 of the drawings.

Gunwales or rowlock-bars *rr* are fixed centrally on top or bottom sides of the floats, and are provided with rowlock-pins *t*, as shown, to

afford a fulcrum for oars, whereby the raft 65 may be propelled. These bars are secured to the floats in the manner shown best in Fig. 3, a broad parallel strip, *s*, being placed under the gunwale-strip on the inside of the float, while bolts extend through the same and fasten 70 the strips firmly to the float. This mode of attaching the rowlock-bars secures a broad bearing on the cylinder of the float and prevents any straining or injury thereto by the stress of the oars. Furthermore these bars, 75 while being secured to the thin metal of the float in a most secure manner, act as keels interiorly and exteriorly on the float, and thereby impart great longitudinal stiffness thereto, which prevents “hogging” and enables the 80 float to effectually resist the shock produced in striking the water when launched.

What we claim is—

1. A hollow float for life-rafts formed of two hermetically-closed tubes, one arranged 85 within the other, with an intervening air-space between them, the inner tube being supported at its ends in the pointed ends of the outer tube and at its middle by a ring or collar, substantially as described, and for the purpose 90 set forth.

2. The combination, with the floats *aa* and main deck *f*, rigidly secured thereto, of the folding end sections, *kk*, and side hinged extensions, *ll*, substantially as described, and for 95 the purpose set forth.

3. The combination, in a life-raft, of the screw-nipples *cc*, having bases fixed to the inner sides of the floats, with the diagonal screw rods or tubes *dd* and central connecting screw crosses, *ee*, substantially as herein 100 shown and described.

4. The combination, with a life-raft, of the folding decks and the pivoted or folding standard *n*, with lines *oo'* extending from each 105 side thereof to opposite ends of the deck, substantially as and for the purpose set forth.

5. The combination, in a life-raft, of the fixed deck *f*, extensible or folding deck-section *k*, with the folding or pivoted standard *n*, 110 and lines *oo'*, extending from said standard respectively to one end of the fixed deck and to one end of the folding section, substantially as herein shown and described.

6. The combination, with the float *a* of a 115 life-raft, of the rowlock-bars *rr*, placed on the exterior of the float and extending longitudinally thereof, parallel bars *ss*, placed beneath the same and on the interior of the float, and bolts *t*, which serve the purpose of bolting the 120 bars to the float, and at the same time their free ends form rowlock-pins, substantially as described.
